DESIGN FOR A BROOCH OR SIMILAR ARTICLE

Fred Jaske, Alameda, and Carl M. Johnson, San Francisco, Calif.; Alwine Jaschke administratrix of said Fred Jaske, deceased

Application April 18, 1936, Serial No. 62,206

Term of patent 3½ years

To all whom it may concern:

Be it known that we, Fred Jaske and Carl M. Johnson, citizens of the United States, residing respectively in Alameda, in the county of Alameda, State of California, and in the city and county of San Francisco, State of California, have invented a new, original, and ornamental Design for a Brooch or Similar Article, of which the following is a specification, reference being had to the accompanying drawing, forming part thereof.

Fig. 1 is a top plan view of a brooch or similar article showing our new design;

Fig. 2 is a side elevational view; and

Fig. 3 is a sectional view taken on line 3—3 of Fig. 1.

We claim:

The ornamental design for a brooch or similar article, substantially as shown.

FRED JASKE.
CARL M. JOHNSON.
